UNITED STATES PATENT OFFICE.

GEORGE HENRY WALL, OF LAMBETH, COUNTY OF SURREY, ENGLAND.

SAFETY WATER-GAGE.

SPECIFICATION forming part of Letters Patent No. 426,154, dated April 22, 1890.

Application filed November 29, 1889. Serial No. 331,933. (No model.) Patented in England October 18, 1888, No. 14,952.

To all whom it may concern:

Be it known that I, GEORGE HENRY WALL, of Lambeth, in the county of Surrey, England, a subject of the Queen of Great Britain, have 5 invented certain new and useful Improvements in Water-Gages, (for which John Dewrance and myself have obtained Letters Patent of Great Britain, No. 14,952, dated October 18, 1888,) of which the following is a specification.

The improvement relates to the class of automatic water-gages for steam-boilers; and the object is to so construct such a gage that the automatic valve can be readily inserted 15 or removed through the front of the arm for examination and cleaning without disturbing the glass or the blow-out and boiler cocks, said valve being located as far as possible from where the sediment and incrustation 20 settles and so placed that it will not close the passage when the gage is being blown out, and when removed a straight opening is left for cleaning the passage to the boiler.

The improvement resides in the arm which 25 is adapted to connect the lower end of the observation-glass to a boiler, said arm being provided with a cock to close the passage between the boiler and the valve-chamber, a cock for blowing out the passage, and a valve 30 which is inserted from the front into a chamber directly beneath the glass and above the blow-out cock, as more particularly herein-after described, and pointed out in the claims.

Referring to the drawings, Figure 1 is a side 35 view of the lower arm of a gage, with parts broken away to show the interior. Fig. 2 is a plan view, with part in section, of the lower arm. Fig. 3 is a side view of the plug. Fig. 4 is a side view of the valve-support, with a 40 modified form of valve.

The letter *a* indicates the lower arm of a water-gage. This arm may be attached to a boiler, as shown, by clamping the front of the boiler between a flange on the arm and a nut 45 which screws upon the threaded end of the arm; or the flange may be bolted to the front of the boiler in the usual manner. From a valve-chamber *b* in this arm lead a passage *c* to the boiler, a passage *d* to the glass *e*, a passage *f* to the blow-out cock, and an opening 50 through the front. The glass *e* is attached to

the arm in the customary manner, and a blow-out cock *g* is screwed into the passage *f* from the chamber *b* under the glass, and it is preferred to place a cock *h* in the passage from 55 the boiler. In the opening through the front is inserted a disk *i*, which bears the arm *j* that forms the valve-support. The inner end of this support projects into the valve-chamber under the glass and above the blow-out 60 passage and loosely supports in its cup-shaped end a valve *m*. This disk *i* is preferably held in place by a plug *k*, which is screwed into the threaded end of the opening, a packing being placed over the end of the disk to make 65 the joint tight. The end of the disk is preferably provided with a handle by which it may be pulled out after the plug has been removed. Of course this plug, instead of being screwed into the end of the arm, may be 70 provided with a flange and be bolted to the end of the arm in the common manner. A lug *l* projects from the valve-support *j* into a groove formed in the arm, in order to hold the support in position with the valve-upright, 75 so that it will work properly. If the glass breaks, the sudden and violent rush of steam and water will force the valve upward against the valve-seat formed at the bottom of the passage leading to the glass and prevent leak- 80 age.

The valve may be readily removed for examination, cleaning, or renewing by unfastening the plug without disturbing the glass or removing the blow-out cock or the boiler-cock when the boiler is under pressure and the valve is as far as possible from where the sediment and incrustation settle. The arm may be blown out without closing the valve, and when the valve is removed a 90 straight opening is left into the boiler, so that a rod may be inserted to clean the passage of any obstruction or incrustation.

I claim as my improvement—

1. An arm for a water-gage, having a valve-chamber from which lead openings to the boiler, the glass, the blow-out, and the front of the arm, and a valve smaller than the diameter of the opening through the front of the arm loosely supported under the opening to 95 the glass by an integral projection from the cap which closes the said opening through 100

the front of the arm, whereby when the said cap is removed the valve is removed with it through the opening, substantially as specified.

5. 2. An arm for a water-gage, having a valve-chamber from which lead openings to the boiler, the glass, the blow-out, and the front of the arm, a disk inserted in the opening through the front of the arm, said disk being provided with an integral projecting valve-

support which loosely holds below the passage leading to the glass, a valve that is smaller than the diameter of the passage leading through the front of the arm, and a plug adapted to hold the disk in position, substantially as specified.

GEORGE HENRY WALL.
